DENTURE CLASP

Leonard E. Johnson, Edgewater, Colo.

Application January 12, 1953, Serial No. 330,843

8 Claims. (Cl. 32—5)

1

This invention relates to prosthetic dentures and dental restorations and appliances of the type characterized by mounting and positioning means detachably engageable with a remaining natural tooth, or teeth, adjacent the denture, restoration, or appliance, and more particularly to the tooth-engageable mounting and positioning means of such devices, and has as an object to provide a novel denture clasp susceptible of association with restorations and dental appliances of various types and diverse particular construction for denture-mounting and denture-positioning coaction with the natural teeth utilized as abutments.

A further object of the invention is to provide a novel and improved denture clasp detachably coactable with an abutment tooth with enhanced security.

A further object of the invention is to provide a novel and improved denture clasp susceptible of convenient and repetitious separation from an associated abutment tooth without deformation or permanent distortion.

A further object of the invention is to provide a novel and improved denture clasp adapted for secure, operative coaction with a selected abutment tooth of any particular conformation appropriate for such use.

A further object of the invention is to provide a novel and improved denture clasp amenable to production in fitted relation with a selected abutment tooth through moderate and facile variation of conventional techniques and laboratory practices.

A further object of the invention is to provide a novel and improved denture clasp that is simple of economical production, characterized by wide utility and pronounced operative advantage, variable in detail with full retention of primary operative relationships, and reliable throughout a long life of practical usefulness.

With the foregoing and other objects in view, my invention consists in the construction, arrangement, and combination of elements as hereinafter set forth, pointed out in my claims, and illustrated by the accompanying drawing, in which—

Figure 1 is a plan view of an exemplary dental restoration as mounted and retained in position of practical use by means of a plurality of clasps typically embodying the principles of the invention.

Figure 2 is a side elevation of the arrangement according to Figure 1.

Figure 3 is a plan view of a relatively more

2

simple dental restoration as positioned for practical use through the agency of clasps embodying the principles of the invention.

Figure 4 is a side elevation of the arrangement according to Figure 3.

Figure 5 is a fragmentary, detail elevation, on a relatively enlarged scale, of a representative denture clasp exemplifying the principles of the invention.

10 Figure 6 is a cross section taken substantially on the indicated line 6—6 of Figure 5.

Figure 7 is an elevation, relatively enlarged, of associated elements requisite to the production of the improved clasps as interrelated at one stage of such production.

Figure 8 is a vertical section medially of the organization shown in Figure 7.

In the art of prosthetic dentistry it is conventional practice to construct partial restorations of diverse particularity as removable and replaceable units characterized by an embedded, rigid, metallic member carrying integral end extensions formed as clasps adapted to embracingly engage with and about sound natural teeth functioning as abutments for the proper support and detachable positioning of the restoration. To accomplish the ends for which they are designed, the clasps associated with partial dentures should engage the abutment teeth to which they are fitted without damage to or occasion for deformation of such teeth and in a manner to positively secure and support the denture for use while facilitating optional and repetitious removal and replacement of the denture, all without the presence of tissue-lacerating and food-trapping features. The design and production of suitable denture clasps has long taxed the ingenuity of technicians with results somewhat less than satisfactory, hence the instant invention is directed to the provision of a novel and improved denture clasp susceptible of production with but slight modification of known techniques and procedures and characterized by enhanced operative properties.

45 Representative of the many particular restorations wherewith the clasps of the instant invention may be utilized with advantage, Figures 1—4, inclusive, illustrate approximate forms of the improvement as developed for and applied to practical use. Figures 1 and 2 show a dental appliance accomplishing the restoration of the four incisors and of the two first molars of a single upper jaw as arranged to be positioned and securely mounted by means of four clasps adapted to engage the second premolar, or bicuspid, and

50 55

the second molar at each side of the jaw, while Figures 3 and 4 show an appliance accomplishing the restoration of the first molar and second premolar, or bicuspid, at one side of a lower jaw as arranged to be positioned and securely mounted by means of two clasps adapted to respectively engage the first premolar, or bicuspid, and the second molar adjacent the ends of the restoration; such appliances being, in and of themselves, conventional and merely typical of restorations with which the novel clasps of the invention may be advantageously employed.

Briefly, in Figures 1 and 2 is shown a rigid, metallic, T-shaped member comprised from a transverse bar 10 and a stem 11 perpendicularly interrelated to project the stem 11 anteriorly of the jaw. The free end of the stem 11 carries four incisor restorations 12 thereon disposed to fill the gap between the canines 13 and the free ends of the bar 10 individually mount a first molar restoration 14 thereon disposed to fill the gap at each side of the jaw between the second molar 15 and the proximate second premolar, or bicuspid, 16. The second molars 15 and second premolars 16 of the disclosure represent sound natural teeth suitable to serve as abutments for anchorage of the appliance through the agency of end-opening, yoke-type clasps 17 integrally and oppositely outstanding from free ends of the bar 10 at the sides of the molar restorations 14 in such individual conformation and disposition as conditions them for the desired tooth coaction. In Figures 3 and 4, the second premolar, or bicuspid, restoration 18 and the first molar restoration 19 are represented as carried by a rigid metallic member, not shown, from the anterior end of which extends an end-opening, yoke-type clasp 17 for engagement with and about the first premolar, or bicuspid, 20 as an abutment and from the posterior end of which extends a side-opening, yoke-type clasp 17' for engagement with and about the second molar 21 as an abutment. End- or side-opening yoke-type clasps in association with and for tooth-engagement to position and operatively mount dental restorations are, in general, old in the arrangements illustrated and in many other particular dispositions, that which distinguishes the clasps of the present invention being a novel construction applicable to either or both of the arms of a given clasp, as hereinafter described, to condition the clasp for automatic, positive, interlocking coaction with the associated abutment tooth in an enhancement of clasp grip readily yieldable to pressures applied for disengagement of the clasp from the tooth.

The essential novelty of the invention, clearly manifest in Figures 5 and 6, resides in a contour of the clasp arm inner walls or faces conformed to and to overlie the maximum bulge zone of the abutment tooth wherewith the particular clasp is adapted to engage, in the provision of a slit intersecting the thickness of either or both of the clasp arms longitudinally thereof and extending from an open end adjacent the clasp arm root to a closed end termination spaced inwardly from the clasp arm tip along the line of maximum tooth bulge as evidenced on the clasp arm inner face or wall, and in an inclination of said slit through the clasp arm thickness such as resists, by virtue of wedging action between the relatively-slidable, adjacent slit faces, flexure of the slit-free clasp arm portion away from the root area of the clasp arm. While the novelties of the invention are manifestly ap-

plicable to side-opening, yoke-type clasps 17' of the general construction represented in plan in Figure 3, Figures 5 and 6 show such novelties as developed in and to modify both arms of an end-opening, yoke-type clasp 17 integrally outstanding from a rigid, metallic, denture base member or bar 22, such as one end of the bar 10. As shown, and is usual practice, the arms 23 and 23' of the clasp 17 taper in elevation and in thickness from maximum at the root of the clasp where it merges with the member or bar 22 to minimum at the spaced, free tips 24 and 24', respectively, of said arms, thus to progressively, and obviously, vary the inherent flexibility of the so-constituted arms. Giving effect to the principles of the invention, the inner, spacedly-opposed faces of the arms 23 and 23' are conformably contoured to overlie the zone of maximum bulge characterizing the abutment tooth wherewith the clasp is to coact, such contouring resulting from molding or casting the clasp arms on and about a replica of the actual tooth, as hereinbelow elaborated, and a slit, 25 for the arm 23 and 25' for the arm 23', divides the width and opens through the thickness of each of the clasp arms in a disposition longitudinally of each arm determined at the arm inner face by the line of maximum inner face concavity, or maximum tooth bulge, and such as to open 10 through the root of the arm at one end and to terminate at the other end in spaced relation inwardly from the arm tip 24 or 24', such slit disposition resulting in the definition of an arm finger portion, 26 for the arm 23 and 26' for the 15 arm 23', having a free end adjacently underlying the root portion of the associated clasp arm and a zone of attachment to said arm not far removed from the arm tip where the arm original thickness has been reduced by normal arm taper 20 to accommodate an available degree of flexure at the junction of the arm finger portion with the arm body from which said finger portion is freed for limited lateral relative swing by virtue of the slit just described. The arm finger portion 26, or 26', is conditioned to engage with its concaved inner face conformably fitted against the inwardly-tapered, or undercut, area of the abutment tooth thereby circumferentially embraced at the gingival side of the tooth line of maximum bulge, thereby introducing occasion for laterally outward swing of the finger portion relative to the associated arm whenever the clasp 17, or 17', is shifted in either direction axially of the abutment tooth to pass the gingival 25 margin of the clasp across the tooth line of maximum bulge, as in initial engagement of the clasp with, or detachment of the clasp from, said tooth. The free length of the arm finger portion 26, or 26', is progressively thicker and correspondingly more resistive to flexure from its junction with the clasp arm to its tip and the associated clasp arm 23, or 23', is progressively thinner and correspondingly less resistive to flexure from said junction and to its tip 24, or 24', whence it follows that the forces incident to clasp shift on the abutment tooth which tend to swing the finger portion free end laterally and outwardly relative to the clasp act through said finger portion, and the associated clasp arm 30 to bind the arm tip 24, or 24', in a close overlay with the tooth bulge zone thereby engaged and to introduce the necessity for a slight springing apart of the clasp arms 23 and 23', as well as outward springing of the finger portions 26 and 26', to permit seating of the clasp on, or separa-

tion of the clasp from, the abutment tooth. Thus, influences tending to unseat the clasp 17, or 17' from coacting relation with the abutment tooth are resisted by the reluctance of the relatively-stiff finger portion 26, or 26', to yield outwardly and by the consequently enhanced grip of the arm tip 24, or 24', against the abutment tooth in reaction to initial outward swing of the finger portion, which resistances and reactions serve to retain the clasp in firmly-seated engagement with the abutment tooth until the unseating influences attain a magnitude adequate to separate the clasp arms 23 and 23' and to simultaneously flex the associated finger portion, or portions, outwardly beyond the superjacent clasp arm reaches.

While embodiments of the concept characterized by a slit 25, or 25', formed with its plane transverse of the associated clasp arm perpendicular to a plane tangent to the tooth maximum bulge throughout the slit length, thus to accommodate relative lateral swing of the finger without resistance other than that deriving from the stiffness of the materials employed, are within the contemplation of the invention, it is expedient in many clasp constructions, particularly those developed from more pliant materials and with relatively thin sections, to augment the resistance of the finger 26, or 26', to outward lateral swing relative to the associated clasp arm through an inclination of the slit transverse plane outwardly and convergently with respect to the arm and finger gingival margin such as operates to develop a wedging action between the adjacently-parallel slit faces when and as the finger is sprung outwardly relative to the clasp arm, such inclination of the slit transverse plane being clearly indicated in Figures 5 and 6. With the slit transverse plane inclined as shown and described, it is obvious that resistance to finger portion outward swing increases as the outward relative displacement of the finger portion increases and it is likewise manifest that the degree of resistance to outward finger swing introduced through inclination of the slit transverse plane may be varied and adjusted at the time of clasp production through appropriate variation in the degree of plane inclination.

Either side- or end-opening, yoke-type clasps incorporating the novel features of the invention in either one or both of the clasp arms are susceptible of production through the application of but slightly modified, known techniques; the significant modifications of conventional techniques requisite for such production being exemplified in Figures 7 and 8. In the last-noted views, the numeral 27 designates a cast facsimile or replica, commonly constituted from plaster, of an abutment tooth to and for which a denture clasp is to be fitted, the development of such replicas and facsimiles as a phase of denture and denture clasp production being a customary incident of conventional laboratory procedure, and the numeral 28 designates the wax mock-up, or pattern, representing the ultimately-desired metallic clasp elements as partially perfected on and in appropriate relation with the facsimile 27 in accordance with established practice. Conventionally, the wax pattern 28 is completed in simulation and in the use position of the ultimately-desired clasp and is then invested, together with its supporting facsimile 27, within a suitable refractory overlay adapted to receive and shape molten metal thereto intro-

duced in replacement for the pattern 28. Adapting the conventional techniques indicated to the production of the novel and improved clasp hereinabove described, the facsimile 27 is first marked, in any suitable manner and by any appropriate means, to clearly indicate thereon the line interjoining successive points of maximum tooth bulge or lateral protrusion and the area to be covered by the clasp is then outlined on the surface of the facsimile as a guide in shaping the pattern 28. Prior to application of the pattern 28 material, the line of tooth maximum bulge is scored or incised into the material of the facsimile 27, as at 29, to groove the facsimile surface at the location and along the length of the slit, or slits, to be developed in the ultimate clasp arms, and thin sheets or laminae 30 of smooth, refractory material, such as mica, are edge-engaged in and shaped to follow the length of the scored or incised grooves 29 in position to simulate the slits 25, or 25', of the finished clasp arms. With the sheets or laminae 30 in place on the facsimile 27 in widths greater than the clasp arm thicknesses, the pattern 28 is shaped and completed on the facsimile and at both sides of said elements 30 with outer edges of the latter projecting beyond the pattern outer surface, whereafter the pattern and the outer edges of the elements 30 are invested in a usual manner and the moulding of the metallic replacement of the pattern is conventionally completed, engagement of the element 30 inner edges in the groove of the facsimile 27 and of the element 30 outer edges in the refractory investment positioning and immobilizing said elements during substitution of molten metal for the wax pattern 28. Casting of the metallic clasp having been completed, the investment is broken away and the clasp unit is separated from the facsimile 27 and elements 30, all in an obvious manner, to leave ready for trimming, polishing, and use the clasp 17 featured by its slits and finger portions in the operative arrangement shown and hereinabove described and in a transverse inclination of the adjacent slit faces determined by the inclination of the elements 30 when and as embedded in and to traverse the material of the pattern 28.

Since changes, variations, and modifications in the form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. A denture clasp comprising an interrupted, yoke-type band adapted to removably and replaceably embrace and to conformably overlie the maximum bulge zone of an abutment tooth and an integral finger portion at the gingival side of said band defined by a slit intersecting the band thickness in registration at its inner edge with the line of maximum tooth bulge and extending at one end through the gingival margin of the band, whereby to condition said finger for independent flexure relative to the band.
2. A denture clasp comprising an interrupted, yoke-type band adapted to removably and replaceably embrace and to conformably overlie the maximum bulge zone of an abutment tooth, the arm portions of said band being tapered in width and in thickness from a substantially rigid, common root area to their relatively more flexible

tips; and an integral finger portion at the gingival side of at least one of said arm portions defined by a slit intersecting the band thickness in registration at its inner edge with the line of maximum tooth bulge, said slit terminating in inwardly spaced relation with the tip of the associated arm and opening to the gingival side of the arm through the root area thereof.

3. A denture clasp comprising an interrupted, yoke-type band adapted to removably and replaceably embrace and to conformably overlie the maximum bulge zone of an abutment tooth, an integral finger portion at the gingival side of said band defined by a slit intersecting the band thickness in registration at its inner edge with the line of maximum tooth bulge, and an inclination of the slit plane laterally and toward the gingival side of the associated arm productive of wedging action in resistance to flexure of said finger portion outwardly of its clasp arm.

4. A denture clasp comprising an interrupted, yoke-type band adapted to removably and replaceably embrace and to conformably overlie the maximum bulge zone of an abutment tooth, the arm portions of said band being tapered in width and in thickness from a substantially rigid, common root area to their relatively more flexible tips, an integral finger portion at the gingival side of at least one of said arm portions defined by a slit intersecting the band thickness in registration at its inner edge with the line of maximum tooth bulge, said slit terminating in inwardly spaced relation with the tip of the associated arm and opening to the gingival side of the arm through the root area thereof, and an inclination of the slit plane laterally and toward the gingival side of the associated arm productive of wedging action in resistance to flexure of said finger portion outwardly of its clasp arm.

5. In a denture clasp characterized by an interrupted, yoke-type band adapted to embrace and to conformably overlie the maximum bulge zone of an abutment tooth, means for detachably clamping said band to and in secure mounted relation on said tooth, said means comprising an integral finger portion at the gingival side of and capable of independent flexure relative to the band defined by a slit intersecting the band thickness in registration at its inner edge with the line of maximum tooth bulge and extending at one end through the gingival margin of the band.

6. In a denture clasp characterized by an interrupted, yoke-type band adapted to embrace and to conformably overlie the maximum bulge zone

of an abutment tooth, means for detachably clamping said band to and in secure mounted relation on said tooth, said means comprising an integral finger portion at the gingival side of the band defined by a slit intersecting the band thickness in inner edge registration with the line of maximum tooth bulge, and an inclination of the slit plane laterally and toward the gingival side of the band productive of wedging action in resistance to flexure of said finger portion outwardly of the band.

7. In a denture clasp characterized by an interrupted, yoke-type band having arm portions tapered in width and thickness from a substantially rigid, common root area to relatively more flexible tips and inner faces on said arm portions contoured to embrace and conformably overlie the maximum bulge zone of an abutment tooth, means for detachably clamping said band to and in secure mounted relation on said tooth, said means comprising an integral finger portion at the gingival side of at least one of said arm portions defined and conditioned for flexure relative to the associated arm portion by a slit intersecting the arm portion thickness in inner edge registration with the line of maximum tooth bulge and opening to the gingival side of the said arm portion through the root area thereof.

8. In a denture clasp characterized by an interrupted, yoke-type band having arm portions tapered in width and thickness from a substantially rigid, common root area to relatively more flexible tips and inner faces on said arm portions contoured to embrace and conformably overlie the maximum bulge zone of an abutment tooth, means for detachably clamping said band to and in secure mounted relation on said tooth, said means comprising an integral finger portion at the gingival side of at least one of said arm portions defined and conditioned for flexure relative to the associated arm portion by a slit intersecting the arm portion thickness in inner edge registration with the line of maximum tooth bulge and opening to the gingival side of the said arm portion through the root area thereof, and an inclination of the slit plane laterally and toward the gingival side of the said arm portion productive of wedging action in resistance to flexure of said finger portion outwardly of the band.
